UNITED STATES PATENT OFFICE

WILLIAM ALEXANDER DION, OF PLAINVILLE, MASSACHUSETTS, ASSIGNOR TO EVANS CASE COMPANY, OF NORTH ATTLEBORO, MASSACHUSETTS, A CORPORATION OF MASSACHUSETTS

VANITY CASE

Application filed August 7, 1930. Serial No. 473,537.

This invention relates to receptacles, but more particularly to vanity cases or the like.

One of the objects of the invention is to provide an article of this character which is simple in construction and economical to produce. Another object is to facilitate the assembly of the case.

Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which are shown the features of a selected embodiment of the invention:

Fig. 1 is a plan view of the case in open position;

Fig. 2 is an enlarged transverse section substantially on the line 2—2 of Fig. 1, the parts being in closed position, and

Fig. 3 is a detail plan view of one section of the case as shown in Fig. 1.

Referring to the drawings, the vanity case as shown comprises sections 10 and 11 hingedly connected in any suitable manner as at 12 and provided with interacting latch members 13 and 14 to temporarily retain the sections in closed position. These sections 10 and 11 may be of any suitable size or shape and the form and arrangement of the various elements or fittings therein may naturally be considerably varied. The section 11 is provided with a recess or well 15 to receive and contain powder or other cosmetic material 16 and a powder puff 17.

The section 10 contains a mirror 18 provided with a hole 19 extending therethrough. This mirror 18, which so far as certain aspects of the invention are concerned may be considered as representative of a fitting generally, is of the polished metal type and is provided about the margin of the hole 19 with a plurality of depending lugs as 21 which act to form a socket or holder into which may be placed a rouge compact as 20 or other article. The mirror 18 has its margin supported by a

shoulder 22 in the section 10 and it is retained in position thereon by interengaging elements as 23 and 24 constituting a snap-fastener respectively attached to the section 10 and the mirror 18 in any suitable manner or formed thereon. In the construction shown the element 23 comprises a plurality of resilient and converging arms 23a which are adapted to engage and yieldingly interlock with the element 24 in the form of a lug or projecting knob.

Preferably the knob 24 is integrally formed with a sheet metal part 24a by which it may readily be soldered to part 18; also the base part 23b of member 23 may be quickly and inexpensively soldered to the bottom of section 10. In the assembly of the various parts the mirror with the compact holder 21 is properly aligned with the side walls of the section, such action substantially aligning the lug 24 with the opening about which extend the arms of the device 23. It is then depressed sufficiently to cause the arms of the element 23 to be forced apart and to spring into interlocking engagement with the lug 24.

It will be noted that the snap fastener 23—24 is self-aligning in the sense that no separate hinge, stop, or other device is required to hold either of its members against side thrust in order to cause its cooperating elements 23—24 to interlock.

The device 23—24 thus snugly holds the compact holder 21 and the mirror 18 in place, holding these parts against objectionable rattling and holding the mirror snugly but yieldingly against the shoulder 22. This form of attachment very materially simplifies the construction of the article and facilitates the assembly of the various elements, thus reducing the cost of production. For example, in the mounting of a mirror as shown, it eliminates the necessity for interfitting flanges, or other means upon the parts which usually required a high degree of precision and careful interfitting to properly hold the parts in place. Also it eliminates the necessity for a close fit between the margins of the case and the part carried by the case. Furthermore, this form of attachment of the mirror or other parts or fittings en-

ables the same to be readily removed when necessary or advisable for any purpose.

It will be seen that there is provided a construction of an essentially practical nature in which the several objects of this invention are attained.

As many possible embodiments may be made of the above invention without departing from the scope thereof, it is to be understood that all matter herein set forth or shown in the accompanying drawings is to be interpreted as illustrative and not in a limiting sense.

I claim:

1. In a device of the class described, a casing element, a fitment for said casing element, and a self-aligning snap-fastener the cooperating elements of which are secured to the faces of said fitment and said casing respectively whereby to permit rapid assemblage of the casing element and the fitment.

2. In a device of the class described, a casing element, a fitment for said casing element, a socket in said fitment adapted to hold a portion of it spaced a definite distance from said casing element, and fastening means constituting an element secured to the under side of said fitment and a cooperating element secured to said casing element securing said parts together at one point and permitting rapid assemblage.

3. In a device of the class described, a casing member having a marginal shoulder, a fitment adapted to rest on said shoulder, and means spaced from said shoulder having a pair of cooperating elements one of which is attached to a face of said casing and the other of which is attached to a face of said fitment to detachably secure said casing and said fitment together.

4. In a device of the class described, a casing member of irregular shape, a flange on said casing member, a fitment adapted to fit within said flange being prevented from relative motion with respect to said casing by said flange, and a single detachable means connecting said casing and said fitment being spaced from said flange and constituting a pair of interlocking elements.

5. In a vanity case, a casing comprising a pair of coacting sections hingedly connected, latch means for retaining the sections in closed position, a mirror fitting within one of said sections, and a self-aligning snap-fastener one of the parts of which is attached to said mirror and the other of the parts of which is attached to one of said sections to connect said mirror thereto.

6. In a vanity case, a casing comprising a pair of sections hingedly connected, latch means for temporarily retaining said sections in closed position, a partition within one of said sections, and means coacting between said partition and the opposing wall of the section constituting the cooperating parts

of a self-aligning snap-fastener to yieldingly retain said partition in place therein.

7. A vanity case comprising a pair of coacting sections, a hinge pin connecting said sections, a latch for temporarily retaining said sections in closed position, a cosmetic holder within one of said sections, and a self-aligning snap-fastener to yieldingly retain said holder therein.

8. A vanity case comprising a pair of relatively movable sections, means for temporarily retaining said case in closed position, a fitting element adapted to be placed within one of said sections, and members connected to the inside of the section wall and the opposing face of the fitting element constituting the cooperating parts of a self-aligning snap-fastener and adapted to yieldingly interlock to retain said element in position therein.

9. A vanity case comprising a pair of hingedly connected sections, latch means for temporarily retaining said sections in closed position, a cosmetic holding well in one of said sections, a mirror in the other section having a hole therein to admit a cosmetic compact, depending lugs formed on said mirror about the margin of said hole to form a socket to hold said compact, and interlocking members on said mirror and the opposing wall of the section in which it is placed acting to retain said mirror in said section, one of said members being resilient and the members being brought into interlocking engagement by pressing one member against the other.

In testimony whereof, I have signed my name to this specification this 25th day of July, 1930.

WILLIAM ALEXANDER DION.
